Primary Examiner — Elizabeth J Oswecki*(74) Attorney, Agent, or Firm* — MH2 Technology Law Group, LLP(57) **CLAIM**

The ornamental design for an indoor parcel lockers, as shown and described.

DESCRIPTION

FIG. 1 is a front perspective view of an indoor parcel locker, showing our new design; and,

FIG. 2 is a front elevation view thereof.

The undisclosed rear views of the indoor parcel locker shown in FIGS. 1 and 2 are not part of the claimed design. The broken lines in the drawings depict unclaimed subject matter and form no part of the design.
